UNITED STATES PATENT OFFICE.

ALPHEUS W. ALTORFER, OF PEORIA, ILLINOIS, ASSIGNOR TO ALTORFER BROS. COMPANY, OF EAST PEORIA, ILLINOIS, A CORPORATION OF ILLINOIS.

WASHING MACHINE.

Application filed May 4, 1927. Serial No. 188,687.

This invention has reference to washing machines and it relates particularly to that type of machine including a centrifugal extractor for the removal of the free water from 5 clothes or other materials for drying purposes.

The invention has for its principal object to provide a means to receive the water expelled by the extractor and to manually direct such water to different points circumferentially of the extractor; including a plurality of shelf members extending in different directions radially from the extractor, the same functioning as drain boards to carry 10 off the water expelled from the extractor and to discharge the same into one or the other of different receptacles, and a rotatable housing having a conduit and a discharge adapted to be brought into coincidence with separable 15 outlets for alternately or successively changing the direction of the flow of the discharged water to one or the other of said drain boards, and thence to different receptacles or into the washing tub.

The invention has for a further object to provide an extractor attachment for washing machines, including a supporting member having an annular conduit intercepted by spaced discharge outlets, one in communication 20 with the washing tub and others in communication respectively with drain boards extending in different directions radially from said extractor; and a housing supported by said member in a manner to adapt the 25 same to be manually and circumferentially adjusted about said extractor, said housing having an annular conduit adapted to receive water expelled by the extractor and having an outlet adapted to be brought coincident 30 with the respective discharge outlets in said supporting member, whereby an attendant may select the point of discharge of water 35 from the extractor and to direct the same to the tub or into different receptacles.

That the invention may be more fully understood, reference is had to the accompanying drawings, forming part of this description, illustrating a preferred embodiment of the invention, in which:—

Fig. 1 is a plan view of so much of a washing machine as is necessary to illustrate the embodiment of my invention thereto, the dotted lines illustrating the position of different receptacles to receive water discharged 50 by the different drain boards;

Fig. 2 is a side elevation of the machine illustrated in Fig. 1;

Fig. 3 is a plan view somewhat as shown in Fig. 1, except that the housing has been omitted and the supporting member is disclosed partly broken away; 60

Fig. 4 is a vertical cross-section showing the extractor attachment and the relation of the parts comprising the same and the water conducting means thereof, and 65

Fig. 5 is a cross-section, in plan, as the same would appear if taken on the line 5—5, Fig. 4.

Like characters of reference denote corresponding parts throughout the figures. 70

The machine illustrated includes a washing tub 1 having a washing element 2 adapted to be operated from a shaft 3 journaled through the bottom of the tub and receiving its power from any suitable source, not shown. 75 The supporting frame for the machine and its operating parts has been omitted.

The extractor attachment includes a vertically disposed centrifugal container or receptacle 4 rotatably connected to a driving part 5, see Fig. 2, which receives its power from the same source, not shown, for operating the tub shaft 3. The upper portion of the receptacle 4 extends up through and is adapted to rotate within a ring-like extension 6 of a laterally extended frame 7 connected to and extending from the tub 1, and the upper surface of said extension 6 is formed or provided with a rather shallow and narrow annular conduit 7 intercepted at predetermined and spaced points by elongated discharge outlets 8, 9 and 10, outlet 8 being in communication with a downwardly extending outlet 8' adapted for the discharge of water into the tub 1; the outlet 9 is in communication with a downwardly extending outlet (not shown) adapted for the discharge of water onto a shelf portion 11, forming a drain board, and the outlet 10 is in communication with a downwardly extending outlet 10', adapted for the discharge of water onto a shelf portion 12, forming a drain board, see Figs. 3 and 4. 90 95

The shelf portions 11 and 12 may, as shown, comprise a single support divided by the partition 13 to provide separate drain boards 105 which extend radially from the extractor in different directions. The surfaces of these drain boards extend downwardly and away from the extractor, see Fig. 4 and said support, forming or providing these drain boards 110

- is connected to extend away from the ring-like extension, and may, if desired be pivotally connected to said extension at 14. Due to the inclination of the drain boards, the outlet 10', and the corresponding outlet in communication with the outlet 9 open out of the side of said extension 6, whereas the outlet 8' leads directly down into the tub 1.
- The peripheral surface of the ring-like extension 6 is tapered downwardly and inwardly, as at 14, see Fig. 4, and its upper surface, next adjacent its inner circumferential edge is provided with an annular groove 15 for purposes to be explained.
- 10 Supported to be manually and circumferentially rotated or adjusted on the ring-like extension 6 is a housing 16. This housing is ring-like in cross-section and is provided with an annular conduit 17 formed by the outer vertical wall, a bottom wall 18 and an inner vertical wall 19, spaced from said outer wall and comparatively shorter than said outer wall, and the bottom wall 18 is provided with a short depending annular rib or flange 20, which, when the housing 16 is in assembled position on the extension 6 rests and rides within the groove 15 in said extension, see Fig. 4. The outer wall of the housing has a depending annular apron 21 which encircles the tapered surface 14 of the extension 6 and is spaced outwardly therefrom, and in the space so formed between these parts and at predetermined points circumferentially of the housing anti-rattling and anti-chattering tapered spacing blocks 22 are provided; certain of which are secured in place by removable screws 23, while one of such blocks has operatively connected thereto the set screw 24 which when turned up will 40 wedge the block against the tapered surface 14 of the extension 6 and lock the housing in its adjusted position. The release of the set screw will permit the housing to be adjusted circumferentially about the extractor, for 45 selectively bringing an outlet opening 25, see Figs. 4 and 5, in the bottom wall 18 of the housing into coincidence with either of the outlets 8, 9 or 10 in the extension 6, for the selective discharge of water expelled by the 50 extractor into the tub 1, or onto the drain board 11 or onto the drain board 12, as it is believed will be understood. It is further obvious from the description that the drain boards 11 and 12 are substantially stationary, 55 when in operative position, and that the housing is movable to be circumferentially adjusted about the extractor for the purpose of directing the discharge of water, expelled by the extractor, to different points about said 60 extractor. To take care of any seepage of water which may enter between the coating surfaces of the housing and its support, the annular conduit 7 is provided, through which water will drain to the discharge outlets 65 thereof.

To properly direct the water expelled from the receptacle 4 into the conduit 17 of the housing, the upper end of the receptacle has an outwardly and downwardly turned flange 26, which normally overlies the upper edge 70 of the wall 19 forming the inner wall of the conduit 17, and a lid 27 adapted to form or provide a closure for the upper open end of the receptacle has a fluted or corrugated edge 75 28 providing water egress passages between the flange of the receptacle and said lid, when the latter is in closed position; the water expelled from the receptacle going out through these passages and taking somewhat the direction indicated by the arrows in Fig. 4. 80

The lid 27 is preferably rotatably connected with a supporting member 29 hinged at 85 30 to one side of the housing 16 and diametrically opposite thereto is adapted to be locked to the housing by a locking means 31. The lid, when the support therefor, is in closed position is adapted to engage with the flange of the receptacle and rotate with the latter when it is in operation.

The top wall of the housing is provided with an enlarged annular opening 32 through which the receptacle 4 may be placed and removed, if desired, after the lid 27 has been raised out of operative position, and while the housing is in position.

The dotted lines in Figs. 1 and 2 show the position in which receptacles may be placed to catch the water discharged by the drain boards 11 and 12. It is obvious that when clothes or materials are passed from such a receptacle into the extractor, these drain boards will catch any drippings, and due to the close position, which the extractor occupies with respect to the tub, any drippings from the clothes or other materials being 100 transferred from the tub to the extractor, will fall back into the tub. Also, it will be observed that the extractor is located closer to one side of the machine than the other side, which makes for convenience of the attendant 110 in handling a washing operation.

What I claim is:—

1. In a centrifugal extractor, in combination, a rotatable receptacle arranged to discharge liquid from its upper end, a drain board having a fixed radial position with respect to said receptacle and below its discharge, a supporting means surrounding said receptacle having discharge outlets, one of which is coincident with said drain board, and a water receiving and conducting member overlying said support and manually and circumferentially adjustable of said receptacle adapted to receive water expelled by said receptacle and having a discharge outlet adapted to be moved into registering position with the outlets of said supporting means, whereby to selectively discharge water through said outlets.

2. In a centrifugal extractor, in combina- 130

tion, a rotatable receptacle arranged to discharge liquid from its upper end, a drain board having a fixed radial position with respect to said receptacle and below its discharge, a supporting means surrounding said receptacle having discharge outlets, one of which is coincident with said drain board, a water receiving and conducting member overlying said support and manually and circumferentially adjustable of said receptacle adapted to receive water expelled by said receptacle and having a discharge outlet adapted to be moved into registering position with the outlets of said supporting means, whereby to selectively discharge water through said outlets, and means for securing said member in different adjusted positions on its support.

3. In a centrifugal extractor, in combination, a rotatable receptacle arranged to discharge liquid from its upper end, a plurality of adjacently placed drain boards having certain radial positions with respect to said receptacle and below its discharge, a supporting means surrounding said receptacle having a plurality of discharge outlets, one each of said outlets being coincident with a drain board and another of said outlets adapted for discharge at a point removed from said drain boards, and a water receiving and conducting member overlying said support and manually and circumferentially adjustable of said receptacle adapted to receive water expelled by said receptacle and having a discharge outlet adapted to be moved into registering position with the outlets of said supporting means, whereby to selectively discharge water through said outlets.

4. In a centrifugal extractor, in combination, a rotatable receptacle arranged to discharge liquid from its upper end, means adapted to be associated with said receptacle as a closure therefor and so disposed in relation thereto as to provide water conducting passages for the discharge of water radially from the receptacle, a supporting means encircling the receptacle, and having discharge outlets at spaced points circumferentially of the receptacle, a pair of adjacently placed drain boards immediately below said supporting means and arranged to receive water discharged through certain of the outlets thereof, and a housing adapted to be carried by said supporting means and manually and circumferentially adjustable thereon, said housing provided with a water conducting conduit into which water is expelled from the receptacle and also provided with a discharge outlet adapted to be moved into registering position with the outlets of said supporting means, whereby to selectively discharge water through said outlets.

5. In a machine of the class described, a ring-like structure carrying a plurality of delivery spouts, a circular track on said structure, a liquid receiver of annular form mounted to move upon said track, said receiver having a discharge opening adapted to deliver liquid to any one of said spouts, the inner wall of said receiver being open throughout, and a rotatable container concentrically arranged with respect to said receiver and having a discharge surface at its upper end in line with the open wall of said receiver.

In witness whereof, I have hereunto affixed my hand this 30th day of April, 1927.

ALPHEUS W. ALTORFER.
